UNITED STATES PATENT OFFICE

2,633,119

PARACHUTE GUN

Martha Mary Bauderer, Port Clinton, Ohio, and
 Eric K. Lotthammer, Jamaica, N. Y.; said
 Lotthammer assignor to said Bauderer

Application April 5, 1951, Serial No. 219,500

1 Claim. (Cl. 124—27)

1

This invention relates to a toy parachute gun. It is an object of the invention to provide a toy parachute gun wherein there is provided two openings so that parachutes can be projected from the two openings and with which there is associated a single trigger that will release automatically upon the single rearward pull thereof first one parachute and then with a continued pull the other parachute.

It is another object of the invention to provide a toy with which children can play that will acquaint the child with the mechanics of a parachute and which will remove the idea of killing with the use of a gun.

Other objects of the invention are to provide a double barrelled toy parachute gun having a single trigger for releasing the two parachutes, which is of simple construction, inexpensive to manufacture, has a minimum number of parts, light in weight, and easy to handle, compact, durable and efficient in operation.

For a better understanding of the invention reference may be had to the following detailed description taken in connection with the accompanying drawing, in which:

Fig. 1 is a perspective top view of the double barrel toy parachute gun embodying the features of the present invention.

Fig. 2 is a longitudinal sectional view of the gun, taken on line 2—2 of Fig. 1.

Fig. 3 is a transverse sectional view taken on line 3—3 of Fig. 2.

Fig. 4 is an elevational view of the parachute used with the gun.

Referring now to the figures, 10 represents a main hollow body, having two parallel openings 11 and 12 therein. The rearward part of these openings are of less diameter than the forward part of the openings. The gun barrel portions 13 and 14 form a part of this main body, and include respectively the openings 11 and 12. In the respective openings are coil springs 14. The narrow part of the openings are of a diameter equivalent to the diameter of the coil springs and serve to retain such springs against lateral displacement as they are compressed. These springs 14 will be compressed into the narrow parts of their openings when the actuating members therein are retracted and retained. The larger diameter part of the openings will retain a toy parachute 15, Fig. 4, and there may be one of these parachutes used in each opening.

A rod 16 is adjustable in each opening and this rod has a hand knob 17 on the rear end of the body portion by which the rod can be pulled through rear opening 18. The forward end of

the rod has an enlargement 19 which can be adjusted in a rearwardly projected sleeve portion 21 of a cupped plunger 22. A suspended member 15 of parachute 15 fits the cup shaped member 22 as the parachute is inserted in the opening.

The bottom of the body 10 has an opening 23 in which are pivoted laterally spaced latch elements 24 and 25 adapted to receive and retain respectively the cup shaped members 22 which have been withdrawn into the openings. Springs 26 and 27 respectively operate upon the latch members to hold them engaged with the cup shaped plunger 22. Each latch has an inclined surface 28 over which the edge of the cup shaped member rides for engagement with shoulder 29 of the latch. This shoulder receives and retains the plunger 22 while the spring 26 and 27 holds the latch pivoted in its latching position. A pivot pin 30 connects the latches 24 and 25 with the body 10.

Depending from the body 10 is a handle 31 formed of separable parts and secured to the body 10. This handle has a front opening 32 into which hand trigger 33 can be withdrawn. This trigger 33 is pivoted on a pivot pin 34 carried by depending projections 35 and 36 on the body 10. A spring 37 is secured by a rivet 38 to the handle and reacts against the trigger 33 to urge the same forwardly on the handle.

The trigger 33 has on its rear end differently elevated surfaces 39 and 40 engageable respectively with the latches 24 and 25 in sequence so that upon a rearward pull of the trigger first the right hand plunger 22 will be released to extract a parachute 15 and then the other latch 25 will be released to project the parachute in the left opening.

The plunger 23 will accordingly push with great force under the action of the spring 14 on the parachute 15 out of the gun and thereafter the parachute will assume its open shape and will gradually lower itself to the ground. A buffer spring 42 engages the rear body of the gun as the plunger 25 is released to assume the shock of the knob 17 against the rear end of the body 10.

By virtue of the rod 16 having its head 19 slideable in the sleeve projection 21 of the plunger member 22, the rounded head 19 can be thrust against a parachute member 15 to work the parachute out of the opening independently of the plunger 22. In this manner the parachute member 15 can be properly located in the concave or cupped plunger 22.

It should now be apparent that there has been

provided a toy parachute having two openings for receiving parachutes and wherein through a single trigger the parachutes can be projected from the gun in sequence and wherein the pole rod for receiving the plunger element upon the latch is adjustable through the plunger element to dislodge a parachute from the opening when it has been stuck therein.

While various changes may be made in the detail construction of the invention, it shall be understood that such changes shall be within the spirit and scope of the present invention as defined by the appended claim.

We claim:

A toy parachute gun having a body with two parallel openings therein and serving as gun barrels, a plunger operable in each opening to receive and project a toy parachute therefrom, a rod connected to the plunger and extending rearwardly through the rear end of the body, a hand knob on the rear end of the rod and adapted to be pulled to retract the plunger, a handle portion depending from the body portion, a trigger pivoted on the body portion and adapted to be retracted into the handle portion, latch elements pivotally connected to the body portion in a bottom opening therein, said latch elements being laterally aligned and engageable respectively with the plunger elements of the respective openings, said trigger having an individual latch element contacting portion engageable with each latch element to pivot the same and to release the plungers, said portions comprising parallel surfaces of said trigger positioned at different distances from

their associated latch element, said trigger being common to both latch element contacting portions, spring elements carried by the body portion and engageable respectively with the latch elements to urge the same toward their latching positions, spring coils surrounding the respective rods and disposed in the respective openings to urge the plungers forwardly in the openings upon release from the respective latch elements, 5 said portion on the trigger element being engageable with the respective latch elements at different degrees of pivotal movement of said trigger whereby the parachutes may be projected sequentially upon continued rearward pull of the trigger, and spring means within the handle portion 10 and bearing against the trigger to pivot the same forwardly and out of the handle.

15 MARTH A MARY BAUDERER.
